UNITED STATES PATENT OFFICE.

WILLIAM V. VAN DERVORT AND NICHOLAS W. VAN DERVORT, OF NEW ANTIOCH, OHIO.

IMPROVEMENT IN CRADLES.

Specification forming part of Letters Patent No. **170,418**, dated November 23, 1875; application filed July 15, 1875.

To all whom it may concern:

Be it known that we, WM. V. VAN DERVORT and NICHOLAS W. VAN DERVORT, of New Antioch, in the county of Clinton and State of Ohio, have invented certain new and useful Improvements in Cradles for Infants; and we do hereby declare the following to be a full, clear, and exact description of the invention, such as will enable others skilled in the art to which it pertains to make and use it, reference being had to the accompanying drawings, which form part of this specification, in which—

Figure 1 is a perspective view of our invention. Fig. 2 is an end view. Figs. 3 and 4 are vertical transverse sections.

This invention has relation to automatic cradles; and consists in the novel construction, combination, and arrangement of parts, having reference particularly to, first, the means of attaching the cradle-body to the base, upon which it rocks, whereby its motion is limited, and whereby, when desired, the cradle may be operated by treadle-power; second, the means of adjusting, automatically, the leverage through which motion is imparted to the cradle, so as to counteract the tendency of the latter to stop when the occupant is at one side; third, the cushioning-springs, so arranged as to destroy the shock which the tilting of the cradle from side to side tends to produce; fourth, the means of imparting vibratory motion to the cradle from suitable clock-work mechanism.

Referring to the accompanying drawings, A designates the tilting cradle-body, and B a rectangular base, upon the transverse bars *b* of which the cradle rocks, being for such purpose provided with rockers C C'. The bars *b* have flanges *b'* on their outer edges, to guide the rockers and prevent the longitudinal movement of the cradle. D D' are intersecting levers, attached, respectively, at one end to the rockers, and at the other to the frame or base B. These levers serve to limit the tilt of the cradle, and to retain it in its proper position upon the bars *b*. The lever D' is prolonged and extended through a slot in the side of the base B, and holds a stirrup, E, by which the foot may be applied to rock the cradle, a

downward pressure causing the cradle to rock toward the operator, and the release of pressure allowing it to rock to the other side. F represents the ballast or counter-balance, attached to the end of the cradle, near the top edge, and made vertically adjustable by means of a set-screw or other suitable device, f. The object of this weight is to overcome that of the occupant, such an expedient being rendered necessary in consequence of the application of the leverage to the cradle near its center. By adjusting the weight F the motion of the cradle may be conveniently regulated. G designates a case containing the cradle-motor, from which power is transmitted, through the crank *e* and connected pitman *e'*, to a rock-beam, *e''*, from the short arm of which rises a stem, *g*, holding a spool, *g'*. H is a cord, wound once around said spool, and having its ends attached to springs I, which are fastened at one end to the cradle, as shown.

When the motor is at work the stem *g* vibrates, and, through its connections with the cradle, rocks the same. The proper or normal position of the spool is midway between the ends of the cord; but should the child occupying the cradle lie more to one side than the other the tension thus brought to bear upon the cord will shift the spool, and thus compensate in leverage for the variation in the position of the weight. The springs I serve as cushions to prevent the shock occasioned by the cradle being suddenly arrested in its motion from side to side. The motor G requires no specific description, being of any ordinary or suitable character. M designates a hook, pivoted to the base B, and engaging with an eye, *m*, in the side of the cradle, for the purpose of holding the latter from rocking, when desired.

Having fully described our invention, we claim—

1. In combination with the cradle A, having the arms D D' pivoted to the rockers and base, and intersecting the treadle, formed of an extension of the arm D', substantially as shown and described.

2. In combination with a cradle rocked by automatic mechanism, the lever *g*, cord H,

and spool g' , for regulating the leverage according to the position of the cradle occupant, substantially as described.

3. In combination with a cradle and automatic mechanism for rocking the same, an intermediate regulator to automatically adjust the rocking-lever to the position of the cradle, as the latter is varied by the motion of the child, substantially as described.

4. The springs I and connection H, in combination with the cradle A and the cradle-motor G, substantially as described.

5. The combination, with the cradle A and motor G, of the cord H, spool g' , stem g , rock-beam e^2 , pitman e^1 , and crank e , substantially as specified.

In testimony that we claim the foregoing we have hereunto set our hands this 28th day of June, 1875.

WILLIAM V. VAN DERVORT.
